[57] ABSTRACT

Amino-containing alkenylsuccinic esters of the formulae

and

where R denotes linear or branched C₁-C₂₀-alkyl, R₁ denotes hydroxy-C₂-C₆-alkyl or C₁-C₄-alkyl, R₂ denotes methyl or ethyl, R₃ denotes C₆-C₂₀-alkyl, preferably C₁₂-C₁₈-alkyl, or C₆-C₂₀-alkenyl, preferably C₁₂-C₁₈-alkenyl, A denotes —C₂H₄— or C₃H₇— and n denotes a number from 1 to 10, preferably from 3 to 8, the preparation thereof and the use thereof as thermostable lubricants in spin finishes.

9 Claims, No Drawings

The Examples which follow are intended to illustrate the invention without limiting it.

EXAMPLE 1

In a 250 ml vessel equipped with stirrer, internal thermometer and short path distillation attachment, 53.38 parts by weight of n-dodeceny succinic anhydride are melted at about 50° C., and 18 parts by weight of N,N-dimethyl ethanolamine are added dropwise with stirring under nitrogen at 50° to 55° C. in the course of 10 30 minutes. The thick emulsion is stirred at 50° C. for 4.5 hours until anhydride is no longer detectable by thin layer chromatography. The mixture is cooled down to 30° C., and 86.3 parts by weight of a coconut alcohol ethoxylate (incorporating 5 ethylene oxide units), 1.2 15 parts by weight of ultrapure boric acid and 1.7 parts by weight of hypophosphorous acid (50% strength) are added. This is followed by 4 hours of stirring at 150°-155° C. under nitrogen, during which a total of 4 ml of water are distilled off. This is followed by distillation under reduced pressure at a temperature between 130° to 155° C. for 3 hours to remove in addition 8 parts by weight of the starting compound, leaving 146 parts by weight of a pale brown, pourable compound having a pH (1% in water) of 6 to 7. 20 25

EXAMPLE 2

Example 1 is repeated, except that n-dodeceny succinic anhydride is replaced by 50 g of i-nonenylsuccinic anhydride. About 45 g of a pale brown liquid having a 30 pH of 7 are obtained.

EXAMPLE 3

In a 500 ml vessel equipped with stirrer, internal thermometer and short path distillation attachment, 70 parts by weight of n-octadecenylsuccinic anhydride are dissolved in 150 parts by volume of tetralin, and 21.6 35 parts by weight of N,N-diethyl ethanolamine are added dropwise with stirring under nitrogen at 35° C. in the course of 30 minutes. The mixture is left to react at 50° 40 C. for 4 hours and then cooled down to room temperature, and 107 parts by weight of stearyl alcohol with 6 moles of ethylene oxide and 3 parts by weight of p-toluenesulfonic acid are added. About 4 ml of water are distilled off at 160° to 180° C. in the course of 2 hours, 45 and then the tetralin is distilled off at 160° C. in an aspirator vacuum and recovered. About 190 parts by weight are obtained of a pale brown, viscous oil having a pH of 7. 50

EXAMPLE 4

Example 2 is repeated, except that the 21.6 parts by weight of N,N-diethyl ethanolamine are replaced by 25 parts by weight of N,N-dimethylbutanolamine. About 193 parts by weight are obtained of a pale brown, viscous oil having a pH of 7. 55

The compounds obtained according to Examples 1 to 4 have the following structures:

-continued

EXAMPLE 5

Heating test: 1 g samples of the following substances are weighed out into a thin aluminum dish which is heated at 220° C. for 24 hours and the losses determined:

- (a) mineral oil (viscosity at 20° C. : 300 mPas)
  - (b) pentaerythritol tetradecylate
  - (c) product according to Example 1
  - (d) product according to Example 2
  - (e) product according to Example 3
  - (f) product according to Example 4
- a+b: comparisons
c-f: according to the invention

	Loss at 220° C./24 h	Residue	Solubility of residue in cold water
(a)	50%	black, solid	insoluble
(b)	60%	black, solid	insoluble
(c)	33%	yellow, greasy	emulsible
(d)	40%	yellow, greasy	emulsible
(e)	35%	yellow, greasy	emulsible
(f)	30%	yellow, greasy	emulsible

EXAMPLE 6

Friction values on PES

Product	Pure oil		5 g/l	
	static	dynamic	static	dynamic
a	8.4	0.44-0.48	8.2	0.49-0.50
b	8.5	0.48-0.59	8.3	0.49-0.55
c	8.9	0.42-0.47	8.0	0.43-0.47
d	8.3	0.44-0.48	8.1	0.44-0.49
e	8.2	0.41-0.46	8.0	0.40-0.45
f	8.2	0.43-0.49	8.1	0.41-0.46

a + b comparisons as per Example 5

c - f Examples 1 to 4 according to the invention

65 These values were determined by the method specified in German Offenlegungsschrift 2,355,675, specifically at measuring speeds of 25 m/min (first value) and 100 m/min (second value).

6

We claim:

1. A compound of the formulae

01

where R denotes linear or branched C₁-C₂₀-alkyl, R₁ denotes hydroxy-C₂-C₆-alkyl or C₁-C₄-alkyl, R₂ denotes methyl or ethyl, R₃ denotes C₆-C₂₀-alkyl, or C₆-C₂₀-alkenyl, A denotes —C₂H₄— or —C₃H₇— and n denotes a number from 1 to 10.

2. A process for preparing a compound as claimed in claim 1, which comprises reacting an alkenylsuccinic acid of the formula

1 30

40

45

50

55

60

65

or the anhydride thereof first with 1 mole of an amine of the formula

and then with 1 mole of an alkoxylated alcohol of the formula

$$\text{R}_3(\text{OA})_n-\text{OH}$$

where R , R_1 , R_2 , R_3 , A and n are as defined in claim 1.

3. A compound as claimed in claim 1, wherein:

R denotes linear or branched C₅-C₁₅ alkyl;

R_3 denotes C₁₂-C₁₈-alkyl or C₁₂

25 n denotes a number from 3 to 8.
4. A compound as claimed in claim 1, wherein R denotes linear or branched C₅-C₁₅ alkyl.

5. A compound as claimed in claim 1, wherein R_3 denotes $C_{10}-C_{15}$ alkyl.

30 6. A compound as claimed in claim 1, wherein R_3

7. A compound as claimed in claim 1, wherein n

35 8. A compound as claimed in claim 5, wherein n denotes a number from 3 to 8.

denotes a number from 3 to 8.

9. A spin-finish composition containing an effective amount of a compound of claim 1 and at least one additional spin-finish component.
